UNITED STATES PATENT OFFICE.

MORTON G. BUNNELL, OF CHICAGO, ILLINOIS, ASSIGNOR TO FREDERICK C. AUSTIN, OF SAME PLACE.

DRAG-SCRAPER.

SPECIFICATION forming part of Letters Patent No. 593,270, dated November 9, 1897.

Application filed March 11, 1897. Serial No. 626,958. (No model.)

To all whom it may concern:

Be it known that I, MORTON G. BUNNELL, a citizen of the United States, residing at Chicago, in the county of Cook and State of Illinois, have invented a certain new and useful Improvement in Drag-Scrapers, of which the following is a specification.

My invention relates to a construction of drag-scraper involving a scoop which is adapted to rest upon and to be drawn along the ground and which is provided with a draft attachment to which a horse or team can be hitched, and also provided with handles whereby it can be manipulated by and at the will of an attendant.

Prior to my invention drag-scrapers of such kind have been provided with rocker-shaped wear plates or strips attached to the under side of the scoop, and they have also been provided with rocker-shaped runners attached to the under side of the scoops and adapted to run upon the ground.

In a drag-scraper characterized by my invention the bottom of the scoop is protected from wear by a curved metal plate which is arranged and adapted to form both a wear-plate and rocker and provided with a plurality of parallel and longitudinally-disposed fins or blades which diminish or taper in width toward their forward ends and which are adapted to penetrate the soil, so as to prevent lateral shift or slew of the scoop during use and at the same time permit the rocker-shaped wear-plate to rest upon the ground. By such arrangement the combined wear and rocker plate can also be readily and economically made and provided with the fins or blades, and after having been thus made it can be readily and securely applied and secured to the scoop.

In the accompanying drawings, Figure 1 is a perspective view of a drag-scraper embodying my invention, the scoop being inverted so as to expose my improved attachment. Fig. 2 is a bottom plan of my improved attachment cast in one piece. Fig. 3 is an edge view of the same. Fig. 4 is a section on line ww in Fig. 2. Fig. 5 is a section on line xx in Fig. 2. Fig. 6 is a plan view of the attachment with the fins or blades made separately from the wear and rocker plate and secured

thereto. Fig. 7 is a section on line yy in Fig. 6. Fig. 8 is a section on line zz in Fig. 6. Fig. 9 is a section corresponding with Fig. 4, but illustrating the rocker-plate stamped up so as to form the blades or fins. Fig. 10 is a section on line $z'z'$ in Fig. 9.

The scoop A is usually formed by suitably stamping or striking up a sheet-metal blank and is provided with suitably-attached handles B B and a swinging draft attachment C.

The combined wear and rocker plate D is of metal and is formed with a marginal flange d, adapted to fit against the under side of the bottom of the scoop and suitably perforated to receive rivets, which are desirably employed as a means for securing the plate to the scoop. The main portion d' of this plate is formed so as to gradually swell or incline on a curve from its forward end, which is nearest the front edge of the scoop, to a point near its rear end and to then recede on a curve to its rear end, as clearly illustrated in several of the figures of the drawings. By reason of such conformation the forward edge of the scoop will normally lie in position for scraping up the soil, but by depressing the handles the forward end of the scoop can be readily tilted up, the curved or bulging wear-plate constituting in such case a fulcrum or rocker. This plate covers the greater portion of the under side of the scoop, and while protecting the same from wear also materially stiffens and strengthens the same.

The combined wear and rocker plate is provided with two or more—preferably a couple—parallel blades or fins E, which are arranged longitudinally along the under side of said plate—that is to say, they extend from front to rear relatively to the scoop. These fins or blades E are in planes perpendicular or substantially so to the bottom of the scoop, and while projecting downwardly from the under side of the wear and rocker plate have their edges formed in general correspondence with the longitudinal curvature of the latter—that is to say, the fin or blade tapers or decreases in width from a point near its rear end toward both its forward end, and preferably it also decreases in width from said point toward its rear end. These blades are adapted to cut into the soil, and hence while guid-

ing the scoop and preventing it from slewing around they will permit the wear and rocker plate to rest upon the ground.

As a preferred arrangement and matter of further and special improvement the wear and rocker plate can be cast with the blades E, as illustrated by Figs. 2 to 5, inclusive. In this way a suitably strong plate can be economically provided. The blades can, however, be made separate from the plate and formed with flanges e, as in Figs. 6, 7, and 8, in which case the flanges can be perforated for rivets and suitably riveted to the wear and rocker plate, as in said figures.

15 As another way, the wear and rocker plate can be made of sheet metal and can be struck up with blades E, as in Figs. 9 and 10, in which case the sides of the blades will be somewhat inclined. I prefer, however, to cast the wear and rocker plate with the blades. In each arrangement, however, I contemplate forming the blades so that they will cut into the soil and permit the wear and rocker plate to rest thereon.

20 25 What I claim as my invention is—
1. A drag-scraper comprising a scoop having a rocker-shaped wear-plate secured to its under side and provided with longitudinally-arranged blades adapted to penetrate the soil

and permit the wear and rocker plate to rest 30 thereon, substantially as described.

2. A drag-scraper comprising a scoop having a rocker-shaped wear-plate secured to its under side and provided with longitudinally-arranged blades, which taper in width toward 35 their forward ends, and which are adapted to penetrate the soil and permit the wear and rocker plate to rest thereon, substantially as described.

3. A drag-scraper comprising a scoop having a rocker-shaped wear-plate secured to its under side and provided with longitudinally-arranged blades integral with said plate and made to taper toward their forward ends, the blades being adapted to penetrate the soil and 40 permit the wear and rocker plate to rest thereon, substantially as described.

4. A drag-scraper comprising a sheet-metal scoop, and a cast-metal wear and rocker plate secured to the under side of the scoop and cast 45 with longitudinally-arranged blades adapted to penetrate the soil and permit the wear and rocker plate to rest thereon, substantially as described.

MORTON G. BUNNELL.
